[57] CLAIM

The ornamental design for a handle for a door or the like, as shown and described.

DESCRIPTION

FIG. 1 is a perspective view of a handle for a door or the like showing my new design, the escutcheon plate being shown in broken lines for illustrative purposes only.

FIG. 2 is a top plan view thereof;

FIG. 3 is a front elevational view thereof;

FIG. 4 is a rear elevational view thereof;

FIG. 5 is a left side elevational view thereof; and

FIG. 6 is a right side elevational view thereof.

Fig. 1.Fig. 2.Fig. 3.Fig. 3.Fig. 4.Fig. 5.Fig. 6.
